UNITED STATES PATENT OFFICE.

JOHN F. ARNOLD, OF TORONTO, ONTARIO, CANADA, ASSIGNOR TO DUNLOP TIRE AND RUBBER GOODS COMPANY, LIMITED, OF TORONTO, ONTARIO, CANADA.

DESIGN FOR AN AUTOMOBILE-TIRE.

52,725.

Specification for Design.

Patented Dec. 10, 1918.

Application filed October 3, 1918. Serial No. 256,757. Term of patent 14 years.

To all whom it may concern:

Be it known that I, JOHN F. ARNOLD, a subject of the King of Great Britain, residing in the city of Toronto, county of York, Province of Ontario, Canada, have invented a new, original, and ornamental Design for Automobile-Tires, of which the following is a specification, reference being had to the accompanying drawing, forming part thereof.

In the drawings—

Figure 1 is a plan view of part of the tread; and

Fig. 2 a cross section of the tire; showing my new design.

I claim:

The ornamental design for an automobile tire, as shown.

Signed at Toronto, Canada, this 26th day of September 1918.

JOHN F. ARNOLD.
